CLAIM

The ornamental design for a tablet case, as shown and described.

DESCRIPTION

FIG. 1 is a top perspective view showing the tablet case in a use state, showing my new design;

FIG. 2 is a bottom perspective view;

FIG. 3 is a front view;

FIG. 4 is a rear view;

FIG. 5 is a left side view;

FIG. 6 is a right side view;

FIG. 7 is a top view;

FIG. 8 is a bottom view;

FIG. 9 is a front perspective view showing the tablet case in an alternate configuration;

FIG. 10 is a rear perspective view thereof;

FIG. 11 is a front perspective view showing the tablet case in another alternate configuration;

FIG. 12 is a rear perspective view thereof;

FIG. 13 is an enlarged detail view of area 13 in FIG. 1; and, FIG. 14 is an enlarged detail view of area 14 in FIG. 2.

The broken lines in the drawings illustrate the portions of the tablet case, which form no part of the claimed design.

The dash-dot-dash broken lines are included to annotate the enlarged views and form no part of the claimed design.

1 Claim, 14 Drawing Sheets
